UNITED STATES PATENT OFFICE.

JOHN L. McCULLOUGH, OF BROOKLYN, NEW YORK, ASSIGNOR TO AUTOMATIC TARGET MACHINE COMPANY, A CORPORATION OF NEW YORK.

TARGET APPARATUS.

SPECIFICATION forming part of Letters Patent No. 708,245, dated September 2, 1902.

Application filed April 30, 1900. Renewed December 31, 1901. Serial No. 87,978. (No model.)

To all whom it may concern:

Be it known that I, JOHN L. McCULLOUGH, a citizen of the United States, residing in the borough of Brooklyn, county of Kings, in the city and State of New York, have invented 5 certain new and useful Improvements in Target Apparatus, of which the following is a specification.

This invention relates to the class of target 10 devices or apparatuses wherein the marksman when he pulls the trigger of the simulated gun or pistol completes an electric circuit which operates an indicator at the target, which points out the part of the target 15 at which he has aimed. Such an apparatus is illustrated in the United States patent granted to me June 2, 1896, under No. 561,124, and in my pending application, Serial No. 8,713, filed March 15, 1900.

20 The present application comprises improvements in an electric pistol or gun and target-indicating mechanism, including a special form of counterbalanced universal mounting for the simulated gun or pistol, all as will 25 be hereinafter minutely and specifically described.

In the drawings, which serve to illustrate 30 an embodiment of the invention, Figure 1 is a longitudinal vertical sectional elevation of the apparatus, and Fig. 2 is a horizontal section of the same in the plane indicated substantially by line x^2 in Fig. 1. These are general views on a relatively small scale. Fig. 3 is a front or face view of the target on a 35 scale double that of the general views, and Fig. 4 is a vertical section of the target in the plane indicated by line x^4 in Fig. 3. Fig. 5 is an enlarged sectional view of the electrical indicator device at the target and the electro- 40 magnetic indicator-lock. Fig. 6 is a detail view of the circuit-closing mechanism and sounder, showing the contact-terminals, the automatic circuit-breaker, the shunt, and the electrical connections; and Fig. 7 is a frag- 45 mentary cross-section of same at line x^7 in Fig. 6. Fig. 8 is a detail view of the target-pistol and trigger-contact. Fig. 9 is a dia- 50 gram of the circuit, shunt, &c. Fig. 10 is a view illustrating another form of indicator and lock at the target.

In the embodiment herein illustrated the

invention is shown as applied in a small and compact target apparatus, comprising as its major elements a casing 1, a simulated pistol 2, supported on a universal mounting, counterbalanced so as to allow freedom in aiming, a target 3, and a circuit-closing device, which permits of operating the apparatus only when a contact-piece shall have been inserted. 55

It may be stated here that the target made 60 from threads and the circuit-closing devices are specifically distinct inventions not claimed herein, and they are illustrated and described merely because they or other similar devices are necessary to the full and clear 65 understanding of the invention which forms the object of this application. Some form of penetrable target is important to the present invention, but not necessarily the specific form of the device herein shown. 70

The pistol or weapon 2 may be of any kind, as no explosive is employed; but it will be, by preference, a pistol of the kind known as "self-cocking"—that is, when the marksman grasps it by the stock in the usual way and 75 pulls on the trigger 4 the hammer will rise and fall. Such constructions are too well known to call for illustration, and only the exterior of such a pistol is shown in Fig. 8. This pistol is fixed on the upper end of a tu- 80 bular supporting-stem 5, which extends down into the casing 1 through an aperture in the top of same, the stem having a weight 6 at its lower end and being universally mounted at 7 in a main carrying-frame 8, which is sus- 85 pended at the target on pivots 9 and has a counterbalance-weight 9^a. Thus supported and counterbalanced the pistol may be moved up and down and rocked from side to side and forward and back within limits, so as to 90 be aimed at any point on the target 3.

The target and its appurtenances will now be described with especial reference to Figs. 3, 4, and 5.

10 is the target-box, which is mounted on 95 the casing 1 opposite to the pistol 2 and has at its front a penetrable target 3, here shown of the usual circular form. This target is of peculiar construction, being composed of strands of yarn or thread placed side by side 100 and drawn across a ring or hoop. Preferably there will be two layers or sets of these strands,

one layer or set crossing the other at right angles or at some angle. The object of this construction is to produce a target that may be penetrated or punctured by a rather blunt 5 instrument which will wedge apart the strands and protrude into view without injury to the target, which latter will, however, present the appearance of a solid or impenetrable surface. The threads or yarn used may be 10 white and the sections of the target be indicated by dark circles marked thereon.

Within the target-box 10, behind the target 3, is a solenoid-indicator, comprising a coil 11, having a pointed sliding core 12, provided 15 with a light spring 13 to retract it. This solenoid is mounted on the upright stem of an L-shaped carrier or arm 14, which springs from the stem 5 of the pistol at the universal mounting 7, so that when the pistol is moved 20 about in aiming the core 12 of the solenoid will move about over the back of the target 3 and quite near it. If a current be sent through the solenoid-coil, this core will be protruded through the target and be visible on 25 the face thereof, indicating to the marksman the point at which the pistol was aimed. Mounted on the same stem or branch of the arm 14, Fig. 5, with the solenoid-indicator is an electromagnet 15, mounted slidably in a 30 suitable bearing 19 on said stem and provided with a light retracting-spring 16. The pole-piece 17 of this magnet plays close to a fixed iron plate 18, and when the magnet is excited by a current passed through its coil it will 35 be drawn forcibly to the plate 18, to which its pole-piece will attach itself. This device forms an indicator-lock, and as the magnet and solenoid are in one circuit and excited simultaneously the arm 14 will be locked by 40 the magnet 15 against any but forcible movement at the time the pointed core of the solenoid is protruded through the target. Hence 45 the liability of movement of the core laterally to the injury of the target while its point is protruded through the latter is obviated. The tip or point of the indicator 12 may contrast in color with the threads of which the target is composed.

Within the casing 1 is mounted the circuit-closing device, sounder, &c., which will now 50 be described, with especial reference to Figs. 6, 7, and 8.

The metal circuit-closer *c* is inserted at a slot 20 into a chute 21, which leads it down to a 55 pocket 22. From this pocket there is a substantially horizontal branch 21^a of the chute, which connects with a vertical portion 21^b, leading to a suitable drawer or receptacle 23. A slide 21^c is mounted in a guide 21^d and is 60 adapted when pushed in to push the circuit-closer lodged in the pocket 22 along the chute 21^a and permit it to fall down the chute 21^b to a lodging-place between two terminals 24 and 24^a in the circuit and situated at opposite sides 65 of the vertical chute 21^b. The circuit-closer thus closes a break in the operating-circuit, which comprises the wires *w* and *w^x* and in-

cludes the solenoid-coil 11, the coil of the locking-magnet 15, the coil of an operating-electro-magnet 25, the functions of which will be 70 hereinafter explained, and a generator 26. There is another normally open break in the circuit. (Seen in Figs. 8 and 9.) This break is between two terminals 27 and 27^a, one of which is carried by the trigger 4. When the 75 trigger is pulled, this break, called the "trigger-break," will be closed, and if there is then a closure at the other break between the terminals 24 and 24^a the closing of the trigger-break will complete the circuit through the 80 several magnets. When the marksman wishes to test his skill, he drops a circuit-closer into the slot 20, and then pulls an operating-slide 28 along a slot 29 by means of a knob or handle 30. This slide has a pendent 85 arm 28^a, which takes behind a stud 31 on the slide 21^c and drives the latter in, and when the knob 30 is let go a spring 32 retracts the slide 28. It should be explained here that the terminal 24 at the lower break is hinged and 90 has an arm 33 and a spring thereunder tending to put the terminal in operative position; but normally this terminal is held drawn back (see full lines in Fig. 6) by a weight 34 on a cord or connector 35. This cord is passed several times about a shaft or arbor 36, and is thence led to the slide 21^c, to which it is secured. Now when the slide 21^c is pushed in the weight 34 will be raised, the first part of the movement allowing the terminal 24 to 100 close back into position to intercept the circuit-closer *c*, as indicated in dotted lines in Fig. 6. When the closer *c* falls in the chute 21^b and closes the lower break in the circuit, the latter may then be completed by pulling 105 the trigger, and thus closing the trigger-break. As the slide 21^c is moved in the arbor 36 is rotated and a ratchet-wheel 37 thereon engages a spring-pawl 38, which holds the weight 34 suspended when the slide 21^c moves back 110 and slackens the cord 35. On the arbor 36 are or may be retarding fan-blades 39. The pawl 38 is connected to an upright 40 on the armature-lever 41 of the magnet 15, so that when the circuit is completed through this 115 magnet by pulling the trigger it will draw down its armature-lever, and thus release the pawl 38, so that the weight 34 may slowly descend, and finally by depressing the arm 33 it will draw back the terminal 24, so as to 120 release the closer *c* and allow it to fall into the casing below or the drawer. This release of the closer *c* breaks the circuit through the magnets. In order that the release of pressure on the trigger after firing and the consequent breaking of the circuit at the terminals 27 and 27^a may not break the circuit through the solenoid and locking-magnet at the target, a shunt-conductor *w'* is provided and a shunt-circuit closer 42, which is closed 125 by an arm 40^a on the upright 40. This shunt when closed by the excitation of the magnet 25 cuts out the trigger-break, so that the circuit through the magnets will not be influ-

enced thereby. As the arm 40^a is drawn down to close the shunt-circuit the pawl 38 will be drawn out of engagement with the teeth of the ratchet-wheel 37, so that the weight 34 5 may descend rather slowly, being retarded by the fan-blades on the arbor 36. During the descent of the weight 34 the core of the solenoid will remain protruded through the target and be visible; but when the weight descends 10 far enough and depresses the arm 33 the terminal 24 will be drawn back and the circuit-closer c allowed to drop out of contact. At this instant the circuit through the solenoid and the magnets 15 and 25 will be broken, 15 the spring 41^a of the armature-lever 41 will elevate the latter, thus putting the pawl 38 in engagement with the ratchet-wheel 37 and at the same time breaking the shunt-circuit at 42.

20 In order to produce a sharp sound when the trigger is pulled, a sounder is employed, which will now be described.

A sounding-box 43 is mounted in a suitable position in the casing, and a flap 44, hinged 25 at 45, is provided with a spring 46, which causes the flap when drawn back and then set free to strike the box 43 and produce the required sound. The slide 28 has a pin 47, which engages an arm 48 on the said flap, so 30 that the latter will be drawn back (see dotted lines, Fig. 6,) when the slide 28 is operated. The flap has on it a suitable catch 49, which when the flap is drawn back engages a catch 50 on the armature-lever 41. Consequently 35 when the trigger is pulled and the circuit closed through the magnet 25 the movement of its armature-lever sets free the flap 44 and allows it to strike the box. The above-described construction is only one of many 40 forms in which the sounder may be made.

The indicator and lock at the target have been described as operated electrically or electromagnetically; but they may be as well operated mechanically. An example of a mechanically-operable device is illustrated in 45 Fig. 10. In the construction therein shown most of the parts are the same as has been described; but the solenoid and locking-magnet are replaced by means for performing the 50 same functions with the aid of compressed air.

To the operating-slide 28 is connected a piston-rod, which carries a piston 51^a, playing in a cylinder 51, whereby whenever the slide is operated air is compressed in the cylinder 55 and forced thence into a receiver 52. From this receiver a pipe 53 leads the air to the target box or chamber 10, where the pipe is coupled to an elastic bulb 54, carried in a holder on the arm 14. The indicator 12^a is 60 secured to the bulb, and when compressed air is admitted to the bulb the expansion of the latter drives the indicator through the target. At the same time the other end of the bulb, which is provided with a brake-shoe 54^a, 65 is pressed against the plate 18 to form a lock or friction brake. To control the admission

of air to the bulb from the receiver, the pipe 53 has in it a spring-cock 55, which is normally closed, but which is opened whenever the shunt-magnet 25 is excited. This is effected by connecting the arm of the cock with the armature-lever 41 by a connector 56. The air is allowed to escape from the bulb by means of a spring-cock 57, which is normally closed and is opened whenever the 70 arm 33 is depressed by the weight 34. A connector 58 connects the arm of the cock 57 with an elbow-lever 59, which is rocked by the arm 33.

The remaining parts are the same as seen 80 in Fig. 6. What has been described herein as a "pistol" will not of course be a real pistol capable of using powder and ball. Indeed it may be or may simulate any sort of weapon or firearm. It is convenient to use the term 85 "pistol;" but this term is only employed as descriptive of the particular device shown. The same may be said respecting the word "trigger" herein used as a name for the part 4 by which the marksman closes the electric 90 circuit. In the apparatus as illustrated herein this part simulates the trigger of a pistol, and it may be constructed and mounted exactly like the trigger of a pistol; but obviously any form of circuit-closer to be operated by the hand or finger can be used as well. The word "trigger" is herein meant to mean any suitable manually-operated circuit-closer at the pistol or weapon.

The circuit-closer c may be any disk or 100 piece of metal which will properly close a circuit between two terminals, and if these pieces be collected in a locked drawer, coffer, or the like they will designate the number of times the target has been operated.

Having thus described my invention, I 105 claim—

1. In a target apparatus, the combination with a penetrable target, a pistol or the like, and a universally-mounted support for the pistol, of an indicator back of the target and connected with the pistol-support, means for operating said indicator to cause it to protrude through the target, and means, controlled by the trigger of the pistol, for setting 110 in operation the said indicator.

2. In a target apparatus, the combination with a penetrable target, a pistol or the like, and a universally-mounted support for the pistol, of an indicator back of the target and 115 connected with the pistol-support, means for operating said indicator to cause it to protrude through the target, an indicator-lock, means for operating said lock and means controlled by the trigger of the pistol for setting 120 in operation the said indicator and lock.

3. In a target apparatus, the combination with a penetrable target, a pistol or the like, and a universally-mounted support for the pistol, of an indicator back of the target and 125 connected with the pistol-support, means for operating said indicator to cause it to pro-

trude through the target, and electrical means, controlled by the trigger of the pistol, for setting in operation the said indicator.

4. In a target apparatus, the combination with a penetrable target, a pistol or the like, and a universally-mounted support for the pistol, of an indicator back of the target and connected with the pistol-support, means for operating said indicator to cause it to protrude through the target, an indicator-lock, means for operating said lock, and electrical means, controlled by the trigger of the pistol, for setting in operation the said indicator and lock.
- 15 5. In a target apparatus, the combination with a target, a pistol or the like, and a universally-mounted support for the pistol, of an electrically-operable indicator back of the target and connected with the pistol-support, an indicator-lock, means for actuating said indicator and lock, and electrical means, controlled by the trigger of the pistol, for setting in operation simultaneously the said indicator and lock operating mechanisms.
- 25 6. In a target apparatus, the combination with a casing supporting the mechanism, a target, a target-box, a pistol mounted on a support on the casing, the said support, universally mounted in the casing, an indicator behind the target and carried by the pistol-support, and means for driving the indicator through the target, of electrical means, controlled by the trigger of the pistol, for setting in operation said indicator-actuating means.
- 35 7. In a target apparatus, the combination with a casing supporting the mechanism, a target, a target-box, a pistol mounted on a support on the casing, the said support, universally mounted in the casing, an indicator behind the target and carried by the pistol-support, means for driving the indicator through the target, an indicator-lock, means for operating said lock, and electrical means controlled by the trigger of the pistol for setting in operation said indicator and lock actuating means.

8. In a target apparatus, the combination with a target, a counterbalanced main frame pivotally suspended at the target, a pistol or the like on a support counterbalanced and jointed universally in said frame, and the said support, of an indicator at the target connected with the pistol-support and adapted to move about the target as the pistol is moved in aiming, means for operating said indicator, and electrical means, controlled by the trigger of the pistol for setting in operation the said indicator-actuating mechanism.

9. In a target apparatus, the combination with the casing, a target-box mounted thereon, a target, and a counterbalanced main frame 8, suspended at the target, of a counterweighted support or stem 5, for the pistol, mounted universally in the frame 8, the arm 14 carried by the stem 5 and extending up into the target-

box, an indicator carried by said arm, and a pistol carried by the said stem 5.

10. In a target apparatus, the combination with a target, a pistol, an electric circuit adapted to be completed by actuating the trigger of the pistol, and a magnet 25 in the said circuit, of the sounding device, comprising a box 43, a hinged flap 44, and its spring 46, the armature-lever of the magnet 25, provided with a hook 50, the hook 49 on the flap 44, adapted to engage the hook 50, and means for drawing back said flap, substantially as set forth.

11. In a target apparatus, the combination with a target adapted to be penetrated without rupture, of a pointed indicator adapted to be protruded through said target, a simulated firearm, and means, controlled by the firing of said firearm, for operating said indicator.

12. In a target apparatus, the combination with a penetrable target, and a universally-mounted pistol capable of being aimed at the target, of a carrier connected with the pistol-mounting and situated back of the target, a solenoid-coil mounted on said carrier, the pointed core 12, of said solenoid serving as an indicator for piercing the target, means for retracting said indicator, and an electric circuit including said solenoid-coil and a generator and adapted to be completed through pressure on the trigger of the pistol, substantially as set forth.

13. In a target apparatus, the combination with a penetrable target, and a universally-mounted pistol capable of being aimed at the target, of a carrier connected with the pistol-mounting and situated back of the target, the solenoid-coil fixed in said carrier, the pointed indicator, 12, forming the movable core for the solenoid, means for retracting said core, the locking-electromagnet, the plate 18, and an electric circuit including the coils of the solenoid and the locking-magnet and adapted to be completed through pressure on the trigger of the pistol, substantially as set forth.

14. In a target apparatus, the combination with a target, a universally-mounted pistol or arm capable of being aimed at any part of said target, a solenoid situated back of the target, means connecting said solenoid with the pistol whereby the solenoid is caused to move with the pistol when the latter is aimed, the core of said solenoid, adapted, when protruded to visually indicate its position on the target, and an electric circuit including said solenoid and a generator and adapted to be completed through pressure on the trigger of the pistol, substantially as set forth.

In witness whereof I have hereunto signed my name, this 27th day of April, 1900, in the presence of two subscribing witnesses.

JOHN L. McCULLOUGH.
